UNITED STATES PATENT OFFICE.

ANDREW DLACICH, OF COLUMBUS, OHIO.

DESIGN FOR A PICK.

56,054.

Specification for Design.

Patented Aug. 10, 1920.

Application filed January 14, 1920. Serial No. 351,484. Term of patent 7 years.

To all whom it may concern:

Be it known that I, ANDREW DLACICH, a citizen of Jugo-Slavia, residing at Columbus, in the county of Franklin and State of Ohio, have invented a new, original, and ornamental Design for a Pick, of which the following is a specification, reference being had to the accompanying drawing, forming part thereof.

The figure is a view in perspective of a pick, showing my new design.

I claim:

The ornamental design for a pick, as shown.

ANDREW DLACICH.

Witnesses.
